UNITED STATES PATENT OFFICE.

EDWARD McCONNELL, OF RICHMOND, VIRGINIA.

SAFETY-PIN.

SPECIFICATION forming part of Letters Patent No. 703,965, dated July 1, 1902.

Application filed April 4, 1902. Serial No. 101,415. (No model.)

To all whom it may concern:

Be it known that I, EDWARD McCONNELL, of Richmond, in the county of Henrico and State of Virginia, have invented certain new 5 and useful Improvements in Safety-Pins; and I hereby declare that the following is a full, clear, and exact description thereof, reference being had to the accompanying drawings, which form part of this specification.

10 This invention is an improvement in safety-pins of the kind illustrated in my Patents No. 406,367, dated July 2, 1889, and No. 590,622, dated September 28, 1897.

The body and pin of my patented pin were 15 made in one piece, the body member being formed of a close spiral coil of resilient wire, a few bends at one end being of larger diameter than the main body of the coil to form a keeper for the pin-point. The other end of 20 the coil was tapered to a point, from which extended an integral rod, which was bent back to form the pin member. The objections to these pins are that it is difficult to make a properly-proportioned durable safety- 25 pin, because the wire strong enough for a large pin would be too stiff and large for the coils, or vice versa, and, again, it is difficult to properly temper such pins so as to produce a strong stiff pin with a sufficiently-pliable 30 body. Another practical objection to the use of the patented pin was the difficulty experienced in inserting the pin-bar through stiff material, the flexibility of the smaller end of coil preventing a firm grasp on the pin-bar, 35 and light materials would crowd into and catch between the convolutions of the coil at the base of the pin or smaller end of the coil, making it difficult and annoying to disengage the pin therefrom. The present invention 40 overcomes all these objections and at the same time improves and facilitates the construction of the pin and enables the pin-rods to be tempered properly independently of the coils and a sufficiently-stiff pin-rod to be used 45 with any desired diameter of wire in the coil-body.

The novel features of the invention upon which protection is desired are set forth in the claims, and the following description of 50 the improved pin illustrated in the accompanying drawings will impart a clear understanding thereof.

In said drawings, Figure 1 is a view of the complete pin. Fig. 2 is a longitudinal section therethrough. Fig. 3 is a longitudinal section showing a slight modification thereof.

The body member A of the pin is formed of a spiral coil of wire. At or near one end of the body the convolutions are slightly enlarged, as at a, to form a keeper for the reception of the pin-point, as described in my 55 said patent. The convolutions at the other end of the body are preferably contracted, giving that end a conical or pointed appearance, as shown at a'.

The pin member B is formed separately from the body member. It is pointed at one end b, but its other end is preferably enlarged, the enlargement being preferably conical, as shown at b', and adapted to fit closely within 60 the smaller end of the body A. Such pin member is slipped point first through the body member from the large to the small end thereof and drawn outward until enlargement b' binds tightly in the reduced portion a' of 65 the body. Then the pin member is returned toward the end a of the body member, forming therewith a complete safety-pin. The end b' of the pin member fitting snugly against a plurality of coils at the end a' of the body 70 member makes the pin immovable and imparts a solidarity to the end a of the body member, which enables the user to get a better hold on the pin and more easily force and direct it through thick materials. If desired, 75 the ends a' b' may be wiped or dipped in solder to securely unite them. After insertion of the pin in the material the part a of the body is grasped and pulled outward, as indicated in dotted lines in Fig. 2, until the point 80 of the pin can enter the keeper a, formed by the larger convolutions of the coil. If it be desired to stiffen the body member, the pin member B may be formed, as shown in Fig. 3, with an extension or bar b² in rear of the enlargement b', which extension will lie within 85 the coil and limit lateral movements or bending thereof. The superior construction and advantages of the improved pin over that shown in my said patent are sufficiently set 90 forth above, and

What I claim as novel, and desire to protect hereby, is—

1. A safety-pin comprising a body member

formed of a coil of wire having a pin-point retainer near one end, and a pin member having one end fitted and secured to a plurality of convolutions of the body member opposite the keeper, the outer portion of said pin member being returned toward the keeper, substantially as described.

2. A safety-pin comprising a body member formed of a coil of wire having its convolutions near one end enlarged to form a keeper, and a pin member having one end passing into and secured to a plurality of the convolutions of the body member at the end opposite the keeper, and its outer portion returned toward the keeper, substantially as described.

3. The herein-described safety-pin consisting of a pin member and a body member, the body member comprising a coil of wire surrounding a straight bar, said bar and coil be-

ing unattached except at the end opposite the shield, as set forth.

4. A safety-pin comprising a body member formed of a coil of wire having a keeper at one end, and a stiffening-bar extending within the coil, and a pin member having one end fitted and secured to a plurality of convolutions of the body member at the end thereof opposite the keeper, and its outer end returned toward the keeper, substantially as described.

In testimony that I claim the foregoing as my own I affix my signature in presence of two witnesses.

EDWARD McCONNELL.

In presence of—

ROBT. B. WHITAKER,
E. H. McCONNELL.
